UNITED STATES PATENT OFFICE.

NATHANIEL EDWARDS, OF WASHINGTON COURT-HOUSE, OHIO, ASSIGNOR OF ONE-HALF TO NORMAN SMITH, OF WASHINGTON COURT-HOUSE, OHIO.

CORN-RECEIVER.

SPECIFICATION forming part of Letters Patent No. 732,838, dated July 7, 1903.

Application filed October 3, 1902. Serial No. 125,840. (No model.)

To all whom it may concern:

Be it known that I, NATHANIEL EDWARDS, a citizen of the United States, residing at Washington Court-House, in the county of Fayette, State of Ohio, have invented certain new and useful Improvements in Corn-
receivers; and I do hereby declare the following to be a full, clear, and exact description of the invention, such as will enable others skilled in the art to which it appertains to make and use the same.

This invention relates to receivers for grains, although it may be used to receive vegetables and other growths as they are harvested; and it has for its object to provide a cheap, simple, and efficient construction which will be more rigid than that shown in my former patent, No. 219,080, granted to me September 2, 1879, and which may be folded readily to occupy a small compass and which may be easily handled.

Other objects and advantages of the invention relate to details of structure and will be understood from the following description. In the drawings forming a portion of this specification, and in which like numerals of reference indicate similar parts in the several views, Figure 1 is a top plan view of a receiver embodying the present invention, the fabric at one corner being broken away to illustrate the pivotal mounting of the leg. Fig. 2 is a section on line 2 2 of Fig. 1. Fig. 3 is an elevation showing the hinge which connects the sections of one side of the frame of the receiver.

Referring now to the drawings, the present receiver comprises four legs or supports 5, each in the form of a channel-iron and comprising a web portion and spaced members 6, connected thereby, and which legs support the frame of the receiver. The frame of the receiver consists of sections 7 of iron or steel in the form of bars, the ends of which are turned at angles, as shown at 8, and are pivotally engaged in perforations in the upper end portions of the members 6 of the legs, so that there is formed a rectangular frame, the legs being free for pivotal movement, so that they may be swung inwardly toward the center of the frame. The lower ends of the legs are pointed, so that they may be easily pressed or driven into the ground to support the frame

at the desired elevation. Over the frame thus formed there is stretched a fabric sheet 10, the edges of which are passed around the sides of the frame and are sewed or otherwise secured, said fabric being stretched to give proper tension thereto. Against the under side of the fabric sheet and diagonally thereof are secured strips 11 of fabric, which serve to reinforce the fabric 10 and prevent excessive sagging thereof. The ends of the reinforcing-strips 11 are continued beyond the corners of the sheet 10 and are doubled upon themselves and sewed to form hems through which are passed loops 12 of rope or other suitable material, which form handles by means of which the receiver may be raised to dump its load into and may be carried from place to place.

In the use of the receiver it may be laid flat upon the ground, or the legs may be swung downwardly to project at right angles to the frame and may be then pressed or driven into the ground, and the fabric sheet will be held free from the ground. After the desired quantity of corn or other growths has been placed in the receiver the latter may be raised and dumped into a wagon, and while the wagon is unloading at the barn or other place of storage the receiver may be receiving a second load.

To facilitate folding of the receiver into small compass, the bars or members forming two opposite sides of the frame are formed of two sections hinged together, as illustrated in Fig. 2, so that the frame and fabric 10 may be folded to occupy one-half of its normal space.

In practice modifications of the specific construction shown may be made, and any suitable materials and proportions may be used for the various parts without departing from the spirit of the invention.

It will be noted that one member of the hinge has a stop against which the other member lies to permit of folding of the sections of the frame from a common plane in one direction. Thus the frame is kept rigid when in use.

What is claimed is—

1. A device for loading grain and similar articles into wagons and bins, consisting of a frame, a fabric stretched upon the frame,

and reinforcing-strips secured diagonally of the under side of the fabric and having handles connected to their ends.

2. A device of the class described comprising a frame having a fabric stretched thereon, said frame being rigid and having legs pivoted to its corners to fold against the fabric or to depend at right angles thereto, reinforcing-strips secured diagonally of the under face of the fabric, and handles secured to the reinforcing-strips.

3. A device of the class described comprising a frame including two sections hinged to-

gether to fold one upon the other, a fabric stretched upon the frame, reinforcing-strips secured diagonally of the under side of the fabric, handles secured to the ends of the strips, and legs pivoted at the corners of the frame to fold against the fabric.

In testimony whereof I affix my signature in presence of two witnesses.

NATHANIEL EDWARDS.
